UNITED STATES PATENT OFFICE.

JOSEPH RODGERS, OF CLARINGTON, OHIO.

IMPROVEMENT IN FEED-WATER HEATERS FOR STEAM-BOILERS.

Specification forming part of Letters Patent No. 126,988, dated May 21, 1872.

Specification describing a new and Improved Heater for Steam-Boilers, invented by JOSEPH RODGERS, of Clarington, in the county of Monroe and State of Ohio.

Figure 1 represents a front view of my improved heater. Fig. 2 is a vertical transverse section of the same on the line *c c*, Fig. 1. Fig. 3 is a detail top view of the same.

Similar letters of reference indicate corresponding parts.

This invention has for its object to economize fuel in the heating of water in steam-boilers, and to insure a more thorough result from the heat. It consists in a novel system of circulation, as hereinafter more fully described.

A A in the drawing represent two cylindrical boilers placed side by side; more may be used in connection with my system of heater. C is the forward mud-drum, arranged transversely under the boilers, and connected therewith by stand-pipes *a a*. D is the back mud-drum, parallel to C, and connected with the boilers by stand-pipes *b b*. From the ends of the mud-drum C project, clear of the boilers, upright pipes E E, from which other pipes F F lead back to the drum D. From each pipe project forward four, more or less, horizontal pipes, G G, to or through the front of the heater, the front ends of said pipes G being closed.

By small pipes *d d* the upper ends of the pipes E are connected with the boilers, as shown. Within the drum C is a smaller concentric pipe, H, to which the feed-water is conveyed through a pipe, e. From the ends of H extend vertical branches *f f* within E, and thence forward pipes *g g* within G G.

The ends of the pipes *g* are open. The feed-water, entering H, branching off into *f* and *g*, escapes at the ends of the latter into the pipes G, flowing back therein through E into the mud-drums C and D, and thence ascending in the stand-pipes *a b* to the boilers. While thus circulating the water is thoroughly heated, the pipes being all exposed to the fire, the system E G especially being directly at the sides of the fire-place, as shown. The steam generated in the pipes E passes through the pipes *d d* directly into the boilers.

Having thus described my invention, I claim as new and desire to secure by Letters Patent—

The drum C, stand-pipe *a*, pipes E G, and tubes *e f g*, combined with a steam-boiler, as and for the purpose described.

JOSEPH RODGERS.
